UNITED STATES PATENT OFFICE.

HARRY B. LOMBARD, OF LYNN, MASSACHUSETTS.

TOUPEE.

1,144,658.

Specification of Letters Patent. Patented June 29, 1915.

Application filed November 3, 1914. Serial No. 870,080.

To all whom it may concern:

Be it known that I, HARRY B. LOMBARD, a subject of Victor Emanuel, King of Italy, residing at Lynn, in the county of Essex 5 and State of Massachusetts, have invented certain new and useful Improvements in Toupees, of which the following is a specification.

My invention relates to toupees intended 10 to be worn upon bald heads, and has for its objects to provide a means by which the natural color of the scalp may be visible, especially at the parting, and elsewhere wherever the hair may become ruffled or dislodged; to prevent the contact of the hair 15 with the scalp, thus avoiding consequent irritation incidental thereto; to eliminate the visibility of the foundation net or other holding fabric which heretofore created an 20 artificial effect in toupees as ordinarily made; to furnish a more comfortable toupee than has heretofore been possible; to provide a foundation for the toupee through 25 which air may circulate freely and allow the heat generated at the scalp to escape without detention; to provide a series of reinforcements designated to make practical a mere skeleton foundation for the toupee 30 much lighter than has heretofore been possible; to provide a special reinforcing ribbon intended to add strength to my skeleton foundation at points where needed, flesh 35 colored (hereinafter described) so as to be invisible from the exterior; to provide a means by which a practical toupee may be made with as little hair as the wearer may desire or need, to maintain a natural effect; and to provide other advantages and results, 40 some of which may be hereinafter referred to in connection with the following description.

In the manufacture of my toupee, in order 45 to get the appearance of the natural flesh color to show through the hair and at the parting, I find it necessary to use a particularly brilliant, composite, unusually-colored fabric at the foundation, which I herein-after refer to as flesh colored. It will be understood, however, that this colored foundation is more or less subdued by the hair woven thereon accordingly as the hair is 50 light, dark or thickly woven, so as to create a natural appearance suitable to any complexion. The result from its use being the 55 creation of a flesh colored appearance

sought, this even though the foundation proper is not in itself actually flesh colored.

I accomplish the objects of my invention as illustrated in the accompanying drawings in which—

Figure 1 shows an inside view of my improved toupee. Fig. 2 is an outside view of my toupee with the hair removed. Fig. 3 is an enlarged, detailed section on the line 3—3 of Fig. 2. Fig. 4 shows my toupee as 60 worn upon the head.

The foundation proper is double and consists of two layers of finely woven flesh colored silk gauze, supplemented at the parting with a section of almost invisible netting 70 (hereinafter specifically described), into the top layer of which foundation the hair is artistically and scientifically woven so as to lie in the desired direction.

In Fig. 1, "A" shows the inner layer of 75 my foundation, which acts as a silk lining soothing and cooling to the scalp and protecting it from the irritation caused by contact with the hair holding layer of the foundation G. This flesh colored lining covers 80 the entire bald portion of the head. I insert at the parting H a section of finely woven, almost invisible, transparent netting. The position of this invisible netting is shown in the drawing as "E" and it extends to 85 bounds "B," "C" and "D." Into this invisible netting the hair at the parting is woven instead of in the hair holding layer 90 G of the foundation, and through the netting the flesh colored silk foundation is visible at the parting, giving the effect of the natural scalp. The double flesh colored foundation enables the gauze "E" to be of the lightest possible weight, if so needed, all strain and wear being cared for by the 95 foundation proper. The use of the gauze "E" tends to modify and subdue the coloring of the foundation at the parting.

The toupee is held in place upon the head 100 by suitable adhesive plaster at the points indicated "X," usually four in number, but more or less as may be found necessary, and to strengthen such portions I add substantial flesh colored ribbon reinforcements "F," intended to care for all strain on and about 105 the points of adhesion.

By the means described I provide a foundation sufficiently strong to meet all requirements, yet so cool and light in weight as to be hardly noticeable when placed upon the 110

head. The hairs woven into this foundation are left in varied lengths that they may be combed and brushed into the live hairs of the head, the intermingling thus giving a result which positively defies detection. By the use of my flesh colored foundation herein described the natural color of the scalp appears at any point where the hair becomes ruffled or dislodged, and a clear and natural 10 parting is ever visible.

I maintain that my improved toupee as herein described is one of the greatest scientific improvements in the art of toupee making, giving as it does a true representation of natural hair growing upon the head, a result heretofore long sought, and of especial and invaluable benefit to those possessed of bald heads.

Having thus described my invention, what 20 I claim as new and desire to secure by Letters Patent is:

1. In a device of the character described, a flesh colored fabric foundation, hairs secured to said foundation leaving a narrow 25 strip thereof uncovered to form a parting line, a strip of transparent netting of a different hue from the foundation secured on the upper surface of said foundation and covering said uncovered parting line, and 30 hairs secured to said strip.

2. In a device of the character described, a flesh colored fabric foundation comprising a plurality of layers, hairs secured to the upper layer of said foundation leaving 35 a narrow strip thereof uncovered to form a parting line, a strip of transparent netting of a different hue from the foundation secured to the upper surface of said foundation and covering said uncovered parting 40 line, and hairs connected to said strip of transparent netting.

3. In a device of the character described, a closely woven flesh colored fabric foundation, hairs secured to said foundation leaving 45 a narrow strip thereof uncovered to form a parting line, a strip of open mesh netting of a different hue from the foundation secured on the upper surface of said foundation and covering said uncovered 50 parting line, and hairs secured to said strip.

4. In a device of the character described, a flesh colored fabric foundation, hairs secured to said foundation leaving a narrow 55 strip thereof uncovered to form a parting line, a strip of netting of a different hue from the foundation secured on the upper surface of said foundation and covering said un-

covered parting line, and reinforcing strips on the underside of said foundation extending parallel with said parting line for securing the edges of said netting to said foundation.

5. In a device of the character described, a flesh colored fabric foundation, hairs secured to said foundation leaving a narrow strip thereof uncovered to form a parting line, and means secured to said foundation for toning the hue of said foundation at the exposed portion thereof at said parting line.

6. In a device of the character described, a flesh colored fabric foundation shaped to entirely cover a bald portion of a head, said foundation comprising an upper and a lower layer of said flesh colored fabric secured together around the edges and disposed in close relation throughout their area and hairs secured directly to said upper layer only, whereby said layers will be free from each other to provide for air circulation therebetween.

7. In a device of the character described, a foundation comprising an upper and a lower layer of flesh-colored gauze fabric secured together around their edges and disposed in close relation throughout their area, hair secured directly to said upper layer only, and means secured to said lower layer for retaining said foundation in position upon the head.

8. In a device of the character described, a foundation comprising an upper and a lower layer of flesh-colored gauze fabric, flesh-colored ribbon reinforcements secured around the edges of said layers, hair secured directly to said upper layer only, and means secured to said lower layer for retaining said foundation in position upon the head.

9. In a device of the character described, a foundation comprising an upper and a lower layer of flesh-colored gauze fabric, hair secured to said upper layer only, flesh-colored ribbon reinforcements secured around the edges of said layers and also on each side and parallel with the parting line of said hair, and means secured to said lower layer for retaining said foundation upon the head.

In testimony whereof I affix my signature in presence of two witnesses.

HARRY B. LOMBARD
